UNITED STATES PATENT OFFICE

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS OF TREATING HYDROCARBON OIL

Application filed October 22, 1923, Serial No. 669,929. Renewed January 12, 1929.

This invention relates to improvements in treating hydrocarbon oils, and refers more particularly to the method of handling the vapors generated from the cracking of petroleum oil, which petroleum oils are of an emulsified nature.

Certain petroleum oils of an asphaltic base, as for example, certain oils from the fields adjacent Long Beach, California, are highly emulsified, yielding upon distillation gasoline emulsified with water and of a cherry-like consistency. As far as I am aware this type of distillate has not yielded sufficiently to treatment and is at present a waste product. To overcome this difficulty is the main purpose of the present invention.

I overcome this difficulty by the fractional condensation of the gaseous water and gasoline vapors, maintaining a condenser at approximately 215° F. and under about 100 pound pressure so that the steam and very low boiling point gasoline will condense together in a subsequent condenser with the emulsifying agent.

The material condensed in such first condenser passes to a cooler while the vapors which are not condensed in the first condenser pass to a second condenser, where stratification of water and gasoline takes place.

The invention will be understood from the following description, reference being had to the accompanying drawing in which the single figure represents a somewhat diagrammatic side elevation and vertical section of an apparatus suitable for carrying out the invention.

Referring to the drawings (1) designates the furnace, in which is mounted the heating element (2) which may take the form of a continuous coil through which the raw oil is fed by means of the raw oil pump (3) from any suitable source of supply. The oil in passing through the coil is subjected to cracking conditions of temperature and pressure, as for example, to a pressure of from 100 pounds, and to an oil temperature of 750° F., depending upon the character of the oil under treatment. The oil passes to the combined expansion chamber and dephlegmator (4) which is provided with the superimposed

spaced pans (5) and baffles (6). The heaviest vapors will be condensed and drawn off near the bottom of the dephlegmator through pipe (7) and control valve (8) leading to cooler (9) having control valve (10). The intermediate vapors, as for example, the coal and gas oil cuts may be drawn through pipe (11) having valve (12), which pipe (11) connects to condenser (13) having control valve (14).

The uncondensed vapors pass out of the top of the dephlegmator through pipe (15) control valve (16) into the primary condenser coil (17). This condenser coil (17) may be maintained at a temperature of say 215° F. and under a pressure of say 100 pounds more or less by suitably controlling the valves (18) and (19). The material which condenses in the primary condenser (17), which will be the bulk of water and the heavier vapors pass out through pipe (20) and trap (21) into the cooler (22), the outlet of which is controlled by valve (23). The uncondensed vapors pass out through pipe (24) to condenser (25), the outlet of which is controlled by valve (26).

The cooler (22) and condenser (25) may be maintained at a temperature of say 60° F. more or less. The arrangement is such that the uncondensable gases and the vapors which are not condensed in the primary condenser (17) will pass into the second condenser (25) while only liquid will enter the cooler (22). It is very probable that by preventing the gases and uncondensed vapors from entering the cooler (22) that the tendency to re-emulsification of the bulk of the water and oil, which is in the cooler (22), will be avoided. While the exact nature of these reactions which tend to cause re-emulsification is not known, nevertheless it has been found that slight differences in the handling of these emulsified oils produce substantial differences in their commercial treatment.

By means of the present invention the emulsifying agent, or such gases or vapors as tend to more readily emulsify are separated from the bulk of the water and re-emulsification thus prevented.

I claim as my invention:

1. A process of treating petroleum oil of an emulsified character, consisting in subjecting such oil to cracking conditions of temperature and pressure, in subjecting the vapors evolved from the oil to dephlegmation, in passing the uncondensed oil and water vapors through a primary condenser maintained at a temperature of substantially 215° F. and under a pressure of substantially a hundred pounds to the square inch, to condense the bulk of such oil and water vapors, in passing the resulting condensate directly through a cooling zone, in withdrawing the uncondensed vapors and gases from said primary condenser without admitting the same to said cooling zone, in subjecting such uncondensed vapors and gases to a further condensing action, and in taking off the material from said condensing zone in a de-emulsified form.

2. A process of treating petroleum oil of an emulsified character, consisting in heating the oil to a cracking temperature under superatmospheric pressure, in subjecting the vapors evolved from the oil to reflux condensation, in passing the uncondensed oil and water vapors through a primary condenser maintained under superatmospheric pressure, and at a temperature below the boiling point of water at the pressure on the condenser, but above the boiling point of water for atmospheric pressure, to condense the greater part of such oil and water vapors, in passing the resulting condensate directly through a cooling zone, in withdrawing the uncondensed vapors and gases from said primary condenser without admitting the same to said cooling zone, in subjecting such uncondensed vapors and gases to a further condensing action, and in taking off the material from said condensing zone in a de-emulsified form.

3. A process of treating petroleum oils of an emulsified character, consisting in heating the oil to a cracking temperature under superatmospheric pressure, passing the vapors evolved from the oil to a zone of dephlegmation, passing the uncondensed oily and watery vapors therefrom through a primary condenser maintained under superatmospheric pressure, and at a temperature below the boiling point of water at that pressure, passing the condensate through a cooling zone, withdrawing the uncondensable gases and uncondensed vapors from the primary condenser and subjecting them to further cooling.

4. A process of treating petroleum oils of an emulsified character, consisting in heating the oil to a cracking temperature, passing vapors therefrom to a zone of dephlegmation in which vapors of a heavier fraction and an intermediate fraction are condensed, separately withdrawing and cooling said fractions, passing the uncondensed vaporous and gaseous products from said zone of dephleg-

mation to a primary condenser maintained at a temperature above the atmospheric boiling temperature of water, and under superatmospheric pressure, separately withdrawing the condensate and uncondensed products from said primary condenser and subjecting each to further cooling action.

GUSTAV EGLOFF.
